(57) **CLAIM**

The ornamental design for an electric connector, as shown and described.

DESCRIPTION

FIG. 1 is a front elevation view of an electric connector, showing our new design;

FIG. 2 is a top plan view thereof;

FIG. 3 is a bottom plan view thereof;

FIG. 4 is a 1st side view thereof;

FIG. 5 is a 2nd side view thereof;

FIG. 6 is a 1st perspective view thereof; and,

FIG. 7 is a 2nd perspective view thereof.

The broken lines in the figures depict internal subject matter only, and form no part of the claimed design.

The shading in the figures shows contour and not surface ornamentation.
